LATCH

William N. Edwards, White Deer, Tex.

Application September 18, 1937, Serial No. 164,516

11 Claims. (Cl. 170—47)

This invention relates to locks and particularly to a lock attachment for windmills, windchargers and the like.

An object of the invention is to provide an automatic means for holding the rudder of a windmill out of the wind in inoperative position.

Another object of the invention is to provide a windmill lock disposed adjacent the mill head and rudder which may be remotely controlled by 10 an operator from a ground or other suitable position.

A further object of the invention is to provide a windmill lock which relieves the strain on the rudder pull out mechanism when the lock operates to hold the rudder in inoperative condition.

A still further object of the invention is to provide a lock mechanism for keeping the rudder engagement latch in retracted position to preclude said engagement until the lock is conditioned by suitable actuation.

Another object of the invention is to provide a means for operating the lock mechanism intermediate said lock and the operator's station.

Other objects will be apparent from the following specification and drawings in which:

Fig. 1 is a fragmental perspective view of a windmill with my lock mechanism positioned thereon.

Fig. 2 is a plan view of the lock showing its 30 associated windmill elements.

Fig. 3 is a cross-sectional view taken on line 3—3 of Fig. 2.

Fig. 4 is a plan view of the primary latch member, part thereof being broken away.

Fig. 5 is a plan view of the lock, showing the latch member in retracted or locked-out position, the cross bar and primary latch lever being shown in cross-section.

Fig. 6 is a plan view of the lock showing the 40 latch member in engagement with a cross bar on the rudder, the rudder cross bar and lever being in cross-section.

Fig. 7 is a plan view of the lock after latch and rudder disengagement and before the secondary 45 latch has been released, the cross bar and lever being shown in cross-section.

Fig. 8 is a fragmental side view of a modified form of my lock with a means for actuating said lock.

Fig. 9 is a plan view of the modified form showing its associated windmill elements.

Fig. 10 is a cross-sectional view taken on line 10—10 of Fig. 9.

Fig. 11 is a cross-sectional view taken on line 55 11—11 of Fig. 8.

The embodiment of my invention is particularly adapted to a windmill 14 and in this environment consists of a windmill head 15 rotatably mounted on a turn table 16, the latter being supported upon a trestled tower structure 17. 5 The front of the head carries a hub 18 to which the spider support for the wind wheel vanes (not shown) is attached. Mounted for vertical reciprocating movement, impelled by the wind wheel, is a pump rod 19 disposed centrally of the turn-table and tower structure. Rearwardly of the head and rotatably supported thereby is a rudder structure 20 comprising two longitudinal angle bars 21 fastened together by cross bars 22. A suitable means for retaining the rudder in resilient 10 operative position longitudinally of the wind wheel axis comprises an expansion spring 23 fastened to a lateral extension 24 on the head, the free end of said spring engaging a cross bar (not shown) of the rudder. This spring urges the 20 rudder toward a contraction spring 25 mounted on a carriage 26 and rigidly fastened to the mill head 15. A means for swinging the rudder out 15 of the wind to place the mill in inoperative condition comprises a chain 27 fastened to the rudder by means of an adjustment rod 28. The chain is led through the mill head and directed to a vertical condition centrally of the tower in any conventional manner such as by a roller 29. The chain may be actuated by the operator from 25 a ground position in any suitable manner or by a modification of the apparatus shown in Fig. 8.

My lock 30 is disposed adjacent the path of the chain intermediate the chain adjustment rod and the point where said chain enters the mill head, and consists of a base 31 having a downwardly extending flange 32 which is fastened to an extension 33 of the mill head by bolts 34. The bottom of the base is provided with a frame 35 (Fig. 3) which holds a grooved roller 36 for receiving the chain 27. A primary latch member 37 is rotatably mounted on the base by means of a pin 38 and is spaced therefrom by a riser 39. The primary latch member has a lock-out notch 40 (Fig. 4) formed in its outer side which is adjacent a deeper and inclined release notch 41, said notches being so disposed as to engage a primary latch lever 42 which is pivotally mounted on the base by a threaded pin 43, and spring-urged toward the lock notch by spring 44 engaging said lever by pin 45 and fastened to pin 38 by suitable washer 46. The lower end of the lever carries a ring member 47 (Fig. 3) through which the chain 27 passes intermediate the roller 36 and adjustment rod 28. The pri- 50 55

mary latch member 37 is spring urged against the lever by an expansion spring 48 (Fig. 3), a pin 49 driven in the side of the primary latch member serving as a positioning means between 5 the spring and said member. The free end of this spring bears against a downward extension 50 on a pivoted secondary latch lever 51. The secondary latch is mounted upon the base 31 by two lugs 52 between which said latch is held by 10 a pivot pin 53. The spring 48 therefore serves to urge the primary latch against the lever 42 and to urge the secondary latch upon an inclined secondary latch catch 54 projecting from said primary latch member. A secondary latch release 15 is provided by a finger 55 rotatably mounted on the primary latch member by a bolt 56. The finger is normally held extended beyond the member into the path of the rudder cross bar by a spring 57 fastened to a pin 58 on the primary latch member. The finger carries an arcuate and pointed secondary latch trip piece 59 which, when the secondary latch is operative, is adapted to trip said member by wedging between the primary latch member and a lug 60 on the 20 secondary latch lever thereby raising the latter 25 to disengage it from the latch catch 54.

The primary latch is devised to hold the rudder in inoperative position or out of the wind and to this end an indentation 61 is formed in it to 30 receive a cross bar 22 on the rudder when the latter is swung adjacent the indentation by means of chain 27 provided the lock is placed in proper condition.

In operation the position of the rudder is 35 changed from that shown in Fig. 1 (in the wind) to the position indicated in Fig. 5 by drawing the chain 27 downwardly. This action swings the rudder substantially 90 degrees so that the cross bar 22 thereon is adjacent the indentation 61 formed in the primary latch member 37. 40 When the cross bar is in the latter position a circular lug or ring 62 fastened on the chain adjacent the adjustment rod 28 contacts the ring member 47 on the primary latch lever. Upon 45 further downward movement of the chain 27, this lug moves the primary latch lever from the lock-out notch 40 to a forward position which allows the primary latch member 37 to be moved outwardly by spring 48 thereby placing the primary latch lever in the deeper inclined notch 41 50 formed in the primary latch member. The latch then engages cross bar 22, as shown in Fig. 6. The downward pressure on the chain is thereafter released and the rudder or vane is held out 55 of the wind, that is, in an inoperative position by indentation 61 for any desired length of time, thus eliminating all strain upon the chain and other associated mechanism.

To place the mill in operative position the 60 chain 27 is pulled downwardly which moves the primary latch lever 42 to a position indicated in Fig. 7. This further movement of the lever retracts the primary latch 37 to a position where the secondary latch lever 51 locks upon the latch catch 54. The chain is then released which permits the rudder to swing clear of indentation 61, and also allows the primary latch lever 42 to move back into the lock-out notch 40 by action 65 of the spring 44. Upon further movement of the rudder away from the indentation 61 the cross bar 22 contacts and swings the release finger 55 whereby trip 59 is introduced between the primary latch lever and the lug 60 on the secondary latch lever 51. This action raised the 70 secondary latch lever above the inclined catch 75

54, and permits the primary latch member 37 to resume the position indicated in Fig. 5.

It will be noted that when the primary latch lever 42 is in the lock out notch 40 the primary latch member 37 is held out of the path of movement of the rudder cross bar and the latter will not engage the indentation 61 until the primary latch lever 42 is moved by the lug 62 on the chain 27. This permits the rudder to swing in or out during normal operation of the mill. The primary latch lever 42 cannot be actuated unless the chain is moved, due to the fact that there is sufficient slack between the chain lug and the rudder.

A modification of my lock is shown in Figs. 8, 9, 15 and 10 and comprises a base 63 having a downward flange 64 fastened to an extension 65 on the mill head 66 by bolts 67. A vane or rudder 68 having a cross bar 82, is mounted for rotation upon the head. A chain 69 adapted to bring 20 the rudder out of the wind, is led to a roller 70 positioned on a bracket 71 beneath the base 63 and is then led in a suitable manner through the mill head as by roller 72. A primary latch member 73 is rotatably mounted on the base by 25 means of a pin 74, and is spaced therefrom by riser 75. A secondary latch lever 76 is pivotally mounted upon the base by pin 77, the primary latch being urged against it by spring 78 hooked to a lug 79 on the mill head. The secondary 30 latch lever has a lock out notch 80 formed therein and an upper notch 81. The notches on the lever are urged into engagement with the primary latch member by spring 790 which is fastened to the base bracket by lug 800. As shown 35 in Figs. 9 and 10, the primary latch lever is in the lock out notch. In this position, the latch member is held out of the path of contact with the rudder cross bar 82 to permit said rudder to swing in or out for wind control.

To operate this lock, the chain 69 is pulled 40 downward causing the rudder to swing inwardly adjacent an indentation 83 on the primary latch member. A secondary chain 84, attached to the lower end of the secondary latch lever, is then 45 pulled downwardly which allows the primary latch member 73 to fall into upper notch 81 on the lever 76. This action brings the indentation 83 on the primary latch member into engagement with the cross bar 82 on the rudder. The lock 50 is then in a position to hold the rudder out of the wind and the downward pressure on the chain 69 can be released. To place the mill in operative position, the chain 84 is again pulled downwardly to permit a curved portion 85 on the lever 55 76 to retract the primary latch member and its indentation 83 away from the cross bar 82, chain 69 taking the position shown in Fig. 9.

It will be understood that in a high wind, the 60 vane or rudder must be free to swing in order to control the mill. For this purpose, the lock means are so constructed that if, during regular 65 operation of the mill in such a wind, the rudder is swung over to the lock, the cross bar 82 contacts the outer edge of the arcuate right hand end of the latch member 73 (as seen in Fig. 9) and swings this end of said member inwardly. The opposite end of latch member 73, moving out the upper notch 81 of the lever 76, is immediately engaged by the lower notch so that the rudder-engaging end of the latch member 76, comprising 70 the indentation 83, is held back out of the path of cross bar 82, leaving the rudder free to swing with the wind. To lock the mill now it is merely necessary to pull chain 84 (Fig. 10) whereby latch 75

member 76 and its indentation 83 springs into engaging position relative to the rudder cross bar.

A novel means of operating the chains 69 and 84 is shown in Fig. 8. These means comprise a 5 swivel member 86 having a circular aperture 87 which slidably receives the windmill pump rod 88. The chain 69 is attached to a vertical rod 89, the lower end of the rod being fastened to the swivel by pin 90. Chain 84, attached to a vertical rod 10 91 which runs slidably through a vertical aperture in the swivel 86, is fastened to a lower swivel member 92. The lower swivel has a circular aperture to receive the pump rod. To preclude any 15 substantial rotation of the swivels, bars 93 are fastened thereto and extend beyond the legs 94 of the windmill trestle, said legs thus limiting 20 swinging movement of the bars 93. The two swivels may be urged or pulled downwardly by any suitable means as for instance a windlass or lever 25 arrangement.

The means of the present invention, while disclosed herein as associated with a windmill, are of such character as to be utilized in other environments where a similar relationship between 25 a driving means and a control is present, the essence of the invention comprising a directive member of a class of a vane or rudder pivotally mounted and a latch member associated therewith for selectively holding the directive member 30 in an inoperative position but adapted to be conditioned in such manner as normally to preclude latching of the directive member so that the latter will remain operative for long periods of time without observation or adjustment on 35 the part of the operator.

What is claimed is:

1. Latch means adapted to be associated with a pivoted vane, said means comprising a latch member pivotally mounted adjacent the path of 40 pivotal movement of the vane, resilient means urging the latch member to pivotal movement into said path, a lever pivotally mounted adjacent and normally holding the latch member out of the path of the vane, means on the latch member for 45 engaging the vane, means for actuating the lever to release the latch member into engagement with the vane, and means to release the vane from such engagement.

2. Latch means adapted to be associated with a 50 pivoted vane, said latch means comprising a latch member pivotally mounted adjacent the path of pivotal movement of the vane, resilient means urging the latch member to pivotal movement into said path, a lever pivotally 55 mounted adjacent and normally holding the latch member out of the path of the vane, means on the latch member for engaging the vane, means for actuating the lever to release the latch member into engagement with the vane, and means to release the vane from such engagement, and to 60 restore the lever to normal position.

3. Latch means adapted to be associated with a 65 pivoted vane, said latch means comprising a primary latch member pivotally mounted adjacent the path of pivotal movement of the vane, a lever pivotally mounted adjacent the latch member, resilient means for urging the latch member into the path of the vane and for 70 yieldably holding the latch member and lever in contact with one another, means whereby the lever normally holds the latch member out of the path of contact with the vane, means on the latch member for engaging the vane, means for swinging the latter to bring the vane and said 75 engaging means into adjacency, means operative

upon attainment of such position for actuating the lever to release the latch member into engagement with the vane, means for further actuating the lever to retract the latch member from engaging relation with the vane, secondary 5 latch means cooperating with the primary latch member and operative upon retraction of the latter for restraining the primary latch member until the vane has moved clear of said engaging means, and trip means contacted by the vane 10 after said clearing movement thereof and releasing the secondary from the primary latch member.

4. Latch means adapted to be associated with a pivotally mounted vane, said latch means comprising a primary latch member pivotally mounted adjacent the path of pivotal movement of the vane, a lever pivotally mounted adjacent the latch member, resilient means for urging the latch member into the path of the vane and for 15 yieldably holding the latch member and lever in contact with one another, means whereby the lever normally holds the latch member out of the path of contact with the vane, means on the latch member for engaging the vane, means for 20 swinging the latter to bring the vane and said engaging means into adjacency, means operative upon attainment of such position for actuating the lever to release the latch member into engagement with the vane, means for further actuating the lever to retract the latch member from 25 engaging relation with the vane, secondary latch means cooperating with the primary latch member and operative upon retraction of the latter for restraining the primary latch member until 30 the vane has moved clear of said engaging means, and means for releasing the primary from the secondary latch member. 35

5. Latch means adapted to be associated with a pivotally mounted vane, said latch means comprising a latch member pivotally mounted adjacent the path of pivotal movement of the vane, a lever pivotally mounted adjacent the latch member, resilient means for urging the latch member toward the path of pivotal movement 40 of the vane and for yieldably holding the lever and latch member in contact with one another, means on the latch member for engaging said vane when the latter is brought adjacent thereto by pivotal movement of the vane, means for adjusting contact relation between the latch member and lever whereby the former in one position is held by the lever out of the path of the vane and in another position is released thereby into said path for engaging the vane and holding the 45 vane inoperative, means for retracting the latch member from the vane by further movement of the lever, means associated with the latch member and operative upon such retraction thereof for holding the latch member retracted to provide for clearing of said engaging means by the 50 vane, and means associated with the latch member and contacted by the vane upon movement of the vane toward operative position for releasing the latch member, said lever and latch member 55 being thereby restored to a normal relation wherein the latter is held out of the path of the vane by the lever.

6. Latch means adapted to be associated with a pivotally mounted vane, said latch means comprising a latch member pivotally mounted adjacent the path of pivotal movement of the vane, resilient means urging the latch member into 60 said path, means on the latch member for engaging the vane, a lever pivotally mounted ad- 65 jacent the latch member, resilient means for urging the latch member into said path, means on the latch member for engaging the vane, a lever pivotally mounted ad- 70 jacent the latch member, resilient means for urging the latch member into said path, means on the latch member for engaging the vane, a lever pivotally mounted ad- 75 jacent the latch member, resilient means for urging the latch member into said path, means on the latch member for engaging the vane, a lever pivotally mounted ad-

jacent the latch member, means on the lever adapted to cause the latter in one position to hold the latch member out of said path and in another position to effect its projection thereto, and means for actuating the lever into said positions.

7. Latch means adapted to be associated with a pivotally mounted vane, said latch means comprising a latch member pivotally mounted adjacent the path of pivotal movement of the vane, resilient means urging the latch member into said path, means on the latch member for engaging the vane, a lever pivotally mounted adjacent the latch member, means on the lever adapted to cause the latter in one position to hold the latch member out of said path and in another position to effect its projection thereto, means for actuating the lever into said positions, and means for yieldably holding the lever in its given positions.

8. Latch means adapted to be associated with a pivotally mounted vane, said latch means comprising a latch member pivotally mounted adjacent the path of pivotal movement of the vane, resilient means urging the latch member into said path, means on the latch member for engaging the vane, a lever pivotally mounted adjacent the latch member, means on the lever adapted to cause the latter in one position to hold the latch member out of said path and in another position to effect its projection thereto, means for actuating the lever into said positions, means for yieldably holding the lever in its given positions, and means on the latch member adapted upon contact of said member by the vane to move the latch member out of the path of the vane.

9. The combination with a longitudinally movable shaft or the like having a pair of independently operable chains, cables or similar devices disposed adjacent thereto and substantially parallel therewith, of a swivel member slidably em-

bracing the shaft and having one of said chains attached thereto for actuation upon slidable movement of the swivel member, said swivel member being provided with an aperture for slidably receiving the other of said chains, and a second swivel member slidably embracing said shaft below the first swivel member and having said other chain attached thereto for actuation upon slidable movement of the second swivel member.

10. A windmill comprising a support, a wind-wheel and vane therefor rotatably mounted on the support, the vane being associated with the wheel for normally facing the latter into the wind, means providing for pivotal movement of the vane relative to the wheel and out of operative relation therewith, upon the imposition of unusual stress upon the vane, means normally restoring the vane to operative alignment with the wheel subsequent to such stresses, a latch member on said support adapted to engage the vane upon pivotal movement of the latter into a position adjacent the latch member, and means to condition the latch member for precluding engagement thereof with the vane to provide for normal uninterrupted operation of the windmill.

11. In combination, a directive member of the class of a vane or rudder mounted for pivotal movement transversely of its longitudinal axis, a movable latch member mounted independently of the directive member, the latter in operative position being disposed relatively remote from the latch member, means normally holding the latch member in the path of pivotal movement of the directive member for engaging the latter upon pivotal movement thereof to a position adjacent the latch member, and means to condition the latch member for normally precluding such engagement upon such pivotal movement of the directive member.

WILLIAM N. EDWARDS.
